UNITED STATES PATENT OFFICE.

WILLIAM L. CASADAY, OF NEW CARLISLE, INDIANA.

SULKY-PLOW.

SPECIFICATION forming part of Letters Patent No. 258,987, dated June 6, 1882.

Application filed March 14, 1882. (No model.)

To all whom it may concern:

Be it known that I, WILLIAM L. CASADAY, of New Carlisle, in the county of St. Joseph and State of Indiana, have invented certain new and useful Improvements in Sulky-Plows; and I do hereby declare the following to be a full, clear, and exact description of the invention, such as will enable others skilled in the art to which it pertains to make and use the same.

My invention relates to sulky-plows, the object being to so construct a plow of this character that the adjustment of the plow will be facilitated, its arrangement and operation simplified, and the whole rendered durable and reliable in operation.

With these ends in view the invention consists in the features of construction and combinations of parts hereinafter fully described, and pointed out in the claims.

In the drawings, Figure 1 is a perspective view of a sulky-plow constructed in accordance with my invention. Fig. 2 is a view in side elevation. Fig. 3 is a plan view; and Fig. 4 is a detached view of the inclined wheel, a portion of the axle, and devices for adjusting the inclined wheel.

A represents a crank-axle provided with the outwardly-projecting arms *a a'*.

B represents the rear section of the plow-beam, to the rear end of which is secured the plow C. The forward end of this section B is provided with outwardly-curved arms *b b*, which embrace the crank *A'* of the axle, and are perforated to receive a pivot-bolt, which passes through said arms and through a perforation of the crank, and is provided with a nut, *b³*, which holds the bolt in position.

D represents the forward section of the plow-beam, perforated at its rear end to adapt it to be pivoted at a central point upon the crank *A'*, which is annularly recessed to receive the section D.

Upon the rear section, B, of the plow-beam is provided an upwardly-projecting bracket, *d*, to which is pivoted a locking-brace, E, whose forward end is provided with a downwardly-projecting lip, *e*, adapted to engage with a catch, *e'*, formed on the forward section, D, of the plow-beam, and thus rigidly connect the beam-sections together, and with a lever, *E'*, for disengaging the brace. To the rear end

of the forward section, D, is pivoted in a bracket, *f*, a plunger, F, extending rearwardly within the rear section, B, and provided with a laterally-projecting stud, *f'*, adapted to extend through an elongated slot, *f²*, formed in the side of the section B.

Upon the arm *a'* of the axle A is mounted a sleeve, G, to the inner end of which is connected one side, *h*, of a seat-frame, H, the opposite side, *h'*, of the latter being perforated to fit upon the inner end of the arm *a* of the axle. The cross-bar *h²* of said frame is adapted to support a seat, H', and is provided with a rearwardly-projecting bracket, *h³*, to which is pivotally secured one end of a notched bar or latch, I, the latter being adapted to engage with a laterally-projecting stud or catch, *i*, on the rear section, B, of the plow-beam.

J represents the tongue of the plow, secured to the sleeve G by a plate, J', and a bolt, *j*, and to the seat-frame by a diagonal brace, *j'*, secured at one end by a bolt, *j²*, which passes through said brace, tongue, and plate, and at its opposite end to the side *h* of the seat-frame, in any suitable manner.

K represents a stud projecting laterally from the inner side of the tongue J to form a foot-rest for the driver. Upon this stud K are pivotally supported two guide-links, *k k*, connected at their upper ends by a perforated head, *k'*, and provided with elongated slots *k²*. Between the links *k k* is guided the front end of the forward section, D, of the plow-beam, the latter being provided with a bolt, *k³*, passing through said section D and through the elongated slots of the links *k k*, and having heads or washers *k⁵*. The latter may be formed integral with the beam-section, if preferred, instead of using a bolt. The links *k k* are normally held at the same degree of inclination relative to the beam as the crank *A'* is to the tongue when the plow is level with the furrow-wheel. The section D of the beam is provided with depending brackets *l*, within which is secured a draft-rod, L.

Upon the outer end of the arm *a* of the axle is pivoted a land-lever, M, and adjacent thereto is mounted a sector, N, to which is rigidly secured the outer end of a diagonal brace, O, the inner end of which is secured to the outer end of the foot-rest K.

Upon the arm *a'* of the axle A is mounted the

land-spindle sleeve P , to which is connected by a curved brace, p , the land-spindle P' , upon which is journaled the land-wheel P^2 .

To the outer end of the sleeve P is secured 5 an arched frame or guard, Q , having lugs or stops q . A coiled spring, R , surrounds said sleeve, and is secured thereto at its inner end, while its outer end is bent to engage with the land-lever M , which is arranged between the 10 stops q of the guard Q , so that its movement is limited by said stops, and the spring is thus protected against undue strain.

The diagonal brace O serves to securely brace the land-wheel side of the axle to the 15 tongue, and by the lifting-lever M the land-wheel may be readily adjusted.

S represents a slotted frame, pivoted at its outer end to the plate J' , secured to the under side of the sleeve G , while its opposite end, s , 20 is adapted to slide within a guide, s' , of said plate, and is provided with an elongated slot, s^2 , within which is arranged a cam, T , secured to the lower end of a vertical rotating shaft, U . The latter passes through a perforated 25 lug, u , projecting from the plate J' , and is pivotally secured at its upper end to a perforated and indented plate or sector, V , rigidly mounted on the furrow side of the frame H , and is provided with a hand-lever, v , to engage sector 30 V . The frame S is provided with two horizontal elongated slots, t , arranged parallel with, but diagonally opposite to, each other. Within these slots t are secured bolts w , which connect the arm W of the furrow-spindle X to said 35 frame. The spindle X is arranged at an angle to the axle A , and carries the furrow-wheel Y at an angle to the ground.

Upon the outer end of the sleeve G is rigidly mounted a sector, Z , while upon the end 40 of the arm a of the axle A is rigidly mounted a lifting-lever, Z' , provided on its inner side with a hand-lever, z , to which is connected a rod, z' , the lower end of which is connected to a dog, z^2 , having a coil-spring, z^3 , surrounding 45 it, and working in perforated lugs z^5 of the sector.

The plow as thus constructed is adapted to operate as follows: When the plow is at work the two sections of the beam are connected and 50 held rigidly together by the locking-brace E . When it becomes necessary to pass an obstruction the driver disengages the brace E by means of the lever E' , when the rear section, B , of the plow will fall and the point of the 55 plow be tilted up out of the ground. The latch I will then engage the catch i on the section B and hold the plow until the lifting-lever Z' is drawn back to lift the plow, when the latch I will be automatically thrown out of engagement 60 with its catch i by means of the stud f' of the plunger F . These devices constitute an automatic lift for the plow, and are fully described and claimed in a separate application for Letters Patent signed by me the 31st day 65 of January, 1882. Hence a fuller and more detailed description of such parts is deemed unnecessary in this application; and I would have

it understood that I reserve to myself the right to claim in separate application such parts of the present device as are herein shown and described, but not claimed. 70

The combination of the plow-beam sections with a crank-axle enables said sections to be moved independently of each other, and the slotted links between which the forward end 75 of the beam is guided enable the heel and point of the plow to be raised vertically until the crank of the axle passes the center, when the heel of the plow will be raised higher than the point. 80

By the improved adjusting devices connected with the furrow-wheel frame the furrow-wheel may be easily adjusted to run either parallel with the land-wheel or at an angle thereto, as 85 may be found necessary to properly adjust the plow.

It will be apparent that many changes and modifications of the details of construction of my improvement may be resorted to without departing from the spirit of my invention. Hence 90 I would have it understood that I do not limit myself to the exact construction shown and described, but reserve to myself the right to make such alterations in form and construction as may properly fall within the scope of my in- 95 vention.

Having fully described my invention, what I claim as new, and desire to secure by Letters Patent, is—

1. In a sulky-plow, the combination, with a 100 crank-axle, of a plow-beam consisting of two independent sections pivotally connected to the crank of the axle, substantially as set forth.

2. In a sulky-plow, the combination, with a 105 crank-axle, of a plow-beam made in sections, one section being pivoted to the crank and the other section pivoted on a bolt extending through the crank, substantially as set forth.

3. In a sulky-plow, the combination, with a 110 crank-axle, of a plow-beam having a rear section provided with arms which embrace the crank of the axle and are pivoted thereto, and a forward section adapted to be centrally pivoted to said crank, substantially as set forth.

4. In a sulky-plow, the combination, with a 115 crank-axle, of a plow-beam consisting of a front and a rear section, said sections being pivotally connected with the crank of the axle, and suitable means for connecting and disconnecting the sections of the beam, substantially as set 120 forth.

5. In a sulky-plow, the combination, with a 125 crank-axle and a frame, of a plow-beam consisting of a rear section and a front section pivotally connected to the crank of the axle, and a depending notched bar or latch pivoted upon said frame and adapted to engage a catch on the rear section of the beam, substantially as set forth.

6. In a sulky-plow, the combination, with a 130 crank-axle and a seat-supporting frame, of a plow-beam consisting of a rear section and a front section pivotally connected to the crank of the axle, a locking-brace pivoted to said rear

- section and adapted to engage a catch on the forward section, a depending notched bar or latch pivoted upon said frame and adapted to engage a catch projecting laterally from the 5 adjacent side of said rear section, and a plunger pivoted to the rear end of said forward section, and having a stud arranged to project laterally through a slot in said rear section to automatically disengage the latch from its 10 catch, substantially as set forth.
7. In a sulky-plow, the combination, with a crank-axle and a sectional plow-beam having the adjacent ends of the forward and rear sections pivoted to the crank of the axle, of a 15 guide adapted to receive the forward end of the front section of the plow-beam and allow of a limited vertical movement thereof, substantially as set forth.
8. In a sulky-plow, the combination, with 20 the tongue and forward end of the plow-beam, of a stud or foot-rest projecting laterally from said tongue and pivotally supporting slotted guide-links, within which are supported laterally-projecting studs of the plow-beam, substantially as set forth.
9. In a sulky-plow, the combination, with a crank-axle, of a plow-beam having its rear section pivotally connected to the crank of the axle and its forward section pivoted at one 25 end to said crank, while its opposite end is provided with laterally-projecting studs which receive slotted guide-links, the latter being pivoted to a projecting stud of the plow-beam, substantially as set forth.
- 30 10. In a sulky-plow, the combination, with an inclined spindle secured at one end to an oscillating plate connected with the axle, of a vertical shaft and a cam or eccentric for im- parting an oscillating movement to said plate, and thereby adjusting the position of the wheel, 40 substantially as set forth.
11. In a sulky-plow, the combination, with the furrow side of the axle and with the tongue, of a sleeve or box mounted on said axle and a plate secured to the under side of said sleeve 45 and tongue, the frame of the furrow-wheel pivoted at one end to the outer end of said plate, while its opposite end is adapted to slide in a guide formed on the inner side of said plate, and is provided with an elongated slot, within which 50 is arranged an operating-cam connected to a rotating shaft adapted to be operated by the driver, substantially as set forth.
12. In a sulky-plow, the combination, with the axle, of a seat-supporting frame secured thereto at one end, while its opposite end is secured upon a sleeve mounted on said axle, a plate or bracket secured to the under side of said sleeve and to the tongue, a furrow-wheel axle-frame pivotally connected to the outer 55 end of said plate, while its inner end is adapted to a guide formed on the inner side of said plate, and is slotted to receive an operating-cam, the latter being connected to a rotating vertical shaft which extends through a perforated 60 and indented plate secured to the adjacent side of the seat-frame, and is provided with a hand-lever or dog whereby the furrow-wheel may be adjusted, substantially as set forth.
- 35 In testimony whereof I have signed this 70 specification in the presence of two subscribing witnesses.

WILLIAM L. CASADAY.
